ABSTRACT

A new and distinct cultivar of *Mandevilla* plant named 'TVMD303', characterized by its upright to broadly spreading plant habit; moderately vigorous growth habit; early and freely flowering habit; large light pink-colored flowers with yellowish orange-colored throats; and good container and garden performance.

1 Drawing Sheet

1

Botanical designation: *Mandevilla sanderi*.
Cultivar denomination: 'TVMD303'.

BACKGROUND OF THE INVENTION

The present invention relates to a new and distinct cultivar of *Mandevilla* plant, botanically known as *Mandevilla sanderi*, and hereinafter referred to by the name 'TVMD303'.

The new *Mandevilla* plant is a product of a planned breeding program conducted by the Inventor in Sao Paulo, Brazil. The objective of the breeding program is to develop new compact and freely flowering *Mandevilla* plants with large attractive flowers that resist fading and good garden performance.

The new *Mandevilla* plant originated from a cross-pollination in September, 2016 in Sao Paulo, Brazil of a proprietary breeding selection of *Mandevilla sanderi* identified as code name TVMD008, not patented, as the female, or seed, parent with a proprietary breeding selection of *Mandevilla sanderi* identified as code name TVMD145, not patented, as the male, or pollen, parent. The new *Mandevilla* plant was discovered and selected by the Inventor as a single flowering plant from within the progeny of the stated cross-pollination grown in a controlled greenhouse environment in Sao Paulo, Brazil in July, 2018.

Asexual reproduction of the new *Mandevilla* plant by terminal stem cuttings in a controlled environment in Sao Paulo, Brazil since December, 2018 has shown that the unique features of this new *Mandevilla* plant are stable and reproduced true to type in successive generations.

SUMMARY OF THE INVENTION

Plants of the new *Mandevilla* have not been observed under all possible combinations of environmental conditions

2

and cultural practices. The phenotype may vary somewhat with variations in environmental conditions such as temperature and light intensity, without, however, any variance in genotype.

5 The following traits have been repeatedly observed and are determined to be the unique characteristics of 'TVMD303'. These characteristics in combination distinguish 'TVMD303' as a new and distinct *Mandevilla* plant:

1. Upright to broadly spreading plant habit.
2. Moderately vigorous growth habit.
- 3 Early and freely flowering habit.
4. Large light pink-colored flowers with yellowish orange-colored throats.
5. Good container and garden performance.

10 Plants of the new *Mandevilla* can be compared to plants of the female parent selection. Plants of the new *Mandevilla* differ primarily from plants of the female parent selection in the following characteristics:

1. Plants of the new *Mandevilla* have larger flowers than plants of the female parent selection.
2. Plants of the new *Mandevilla* have lighter pink-colored flowers than plants of the female parent selection.

15 Plants of the new *Mandevilla* can be compared to plants of the male parent selection. Plants of the new *Mandevilla* differ primarily from plants of the male parent selection in the following characteristics:

1. Plants of the new *Mandevilla* have smaller flowers than plants of the male parent selection.
2. Plants of the new *Mandevilla* have light pink-colored flowers with yellowish orange-colored throats whereas plants of the male parent selection have white-colored flowers.

20 Plants of the new *Mandevilla* can also be compared to plants of *Mandevilla sanderi* 'SummerStar Pink', not pat-

ented. In side-by-side comparisons, plants of the new *Mandevilla* differ primarily from plants 'SummerStar Pink' in flower color as flowers of plants of the new *Mandevilla* are light pink in color with yellowish orange-colored throats whereas flowers of plants of 'SummerStar Pink' are reddish 5 purple in color with pink-colored throats.

BRIEF DESCRIPTION OF THE PHOTOGRAPH

The accompanying colored photograph illustrates the 10 overall appearance of the new *Mandevilla* plant showing the colors as true as it is reasonably possible to obtain in colored reproductions of this type. Colors in the photograph may differ slightly from the color values cited in the detailed 15 botanical description which accurately describe the actual colors of the new *Mandevilla* plant.

The photograph is a side perspective view of a typical 15 flowering plant of 'TVMD303' grown in a container.

DETAILED BOTANICAL DESCRIPTION

The aforementioned photograph and following observations, measurements and values describe plants grown during the summer in 15-cm containers in a polyethylene-covered greenhouse in Sao Paulo, Brazil and under cultural 20 practices typical of commercial *Mandevilla* production. During the production of the plants, day temperatures ranged from 20° C. to 35° C. and night temperatures ranged from 10° C. to 20° C. Plants were pinched three times: four weeks, six weeks and eight weeks after planting. Plants were 25 33 weeks old when the photograph and description were taken. In the following description, color references are made to The Royal Horticultural Society Colour Chart, 2015 Edition, except where general terms of ordinary dictionary significance are used.

Botanical classification: *Mandevilla sanderi* 'TVMD303'.

Parentage:

Female, or seed, parent.—Proprietary selection of *Mandevilla sanderi* identified as code number TVMD008, not patented.

Male, or pollen, parent.—Proprietary selection of *Mandevilla sanderi* identified as code number TVMD145, not patented.

Propagation:

Type.—By vegetative cuttings.

Time to initiate roots, summer.—About three weeks at temperatures about 20° C. to 35° C.

Time to initiate roots, winter.—About three weeks at temperatures about 20° C. to 25° C.

Time to produce a rooted young plant, summer.—About 20 to 25 days at temperatures about 20° C. to 35° C.

Time to produce a rooted young plant, winter.—About 25 to 30 days at temperature about 20° C. to 25° C.

Root description.—Thick, fleshy; typically white in 55 color, actual color of the roots is dependent on substrate composition, water quality, fertilizers, substrate temperature and physiological age of roots.

Rooting habit.—Low branching; medium density.

Plant description:

Plant and growth habit.—Upright to broadly spreading plant habit; roughly broadly obovate in overall shape; moderately vigorous growth habit and moderate growth rate.

Plant height, soil level to top of foliar plane.—About 65 30 cm.

Plant height, soil level to top of floral plane.—About 33 cm.

Plant diameter (spread).—About 27 cm.

Lateral branch description.—Branching habit: Moderate branching habit, typically about two primary lateral branches each with about two secondary lateral branches. Length: About 12.5 cm. Diameter: About 2.5 mm. Internode length: About 1.4 cm. Aspect: Primary lateral branches, mostly upright; secondary lateral branches, about 30° from primary branch axis. Strength: Moderately strong. Texture and luster: Smooth, glabrous; semi-glossy; becoming woody with development. Color, developing: Close to 144B. Color, developed: Close to 144A; when woody, close to N199C.

Leaf description:

Arrangement.—Opposite, simple.

Length.—About 6.1 cm.

Width.—About 4.1 cm.

Shape.—Ovate.

Apex.—Acuminate.

Base.—Cordate.

Margin.—Entire.

Texture and luster, upper surface.—Smooth, glabrous; moderately coriaceous; glossy.

Texture and luster, lower surface.—Smooth, glabrous; moderately coriaceous; moderately glossy.

Venation pattern.—Pinnate.

Color.—Developing leaves, upper surface: Close to 139B. Developing leaves, lower surface: Close to 144A. Fully expanded leaves, upper surface: Close to 139A; venation, close to 144C. Fully expanded leaves, lower surface: Close to 144A; venation, close to 137A.

Petioles.—Length: About 1.4 cm. Diameter: About 1.7 mm. Strength: Moderately strong. Texture and luster, upper and lower surfaces: Smooth, glabrous; slightly glossy. Color, upper surface: Close to 144A. Color, lower surface: Close to 144B.

Flower description:

Flower type and flowering habit.—Single salverform flowers arranged in terminal and axillary cymes; flowers face mostly outwardly to slightly upright; freely flowering habit with about two fully open flowers per inflorescence and about 21 flower buds and open flowers per plant.

Natural flowering season.—Plants flower continuously year-round in Brazil; plants begin flowering about 25 weeks after planting rooted young plants.

Flower longevity on the plant.—Individual flowers last about ten days; flowers not persistent.

Fragrance.—None detected.

Inflorescence height.—About 13 cm.

Inflorescence diameter.—About 10 cm.

Flower buds.—Length: About 6.4 cm. Diameter: About 1.3 cm. Shape: Lanceolate. Texture and luster: Smooth, glabrous; slightly to moderately glossy. Color: Distally, close to 56A; mid-section, close to 149D and proximally, close to 149C.

Flowers.—Appearance: Flared trumpet, corolla fused and five-parted. Diameter: About 6.5 cm by 6.5 cm. Depth (length): About 4.8 cm. Throat diameter: About 1 cm. Tube length: About 1.6 cm. Tube diameter: About 3.2 mm.

Corolla.—Quantity and arrangement: Five petals arranged in a single whorl; lower 50% portion of the petals are fused into a funnelform tube. Petal length: About 2.5 cm. Petal width: About 2.3 cm. Petal shape and appearance: Roughly unequal and asymmetric; somewhat spatulate; slightly convex. Petal apex: Acute. Petal margin: Entire; slightly undulate. Petal texture and luster, upper and lower surfaces: Smooth, glabrous; slightly glossy. Throat texture: Smooth, glabrous. Tube texture: Smooth, glabrous. Color: Petal, when opening and fully opened, upper surface: Close to 62B; venation, close to 62B; color does not change with subsequent development. Petal, when opening and fully opened, lower surface: Close to 62C; venation, close to 62C; color does not change with subsequent development. Throat: Close to 14A; venation, close to 14A. Tube: Close to 145B; venation, close to 145B.

Sepals.—Quantity and arrangement: Five sepals arranged in a single whorl. Length: About 8.6 mm. Width: About 3 mm. Shape: Lanceolate. Apex: Acuminate. Base: Broadly cuneate and fused. Margin: Entire. Texture and luster, upper surface: Smooth, glabrous; slightly glossy. Texture and luster, lower surface: Smooth, glabrous; matte. Color: When developing, upper surface: Close to 144C. When developing, lower surface: Close to 145B. Fully developed, upper surface: Close to 144D. Fully developed, lower surface: Close to 145C.

Peduncles.—Length: About 3.4 cm. Diameter: About 1.7 mm. Strength: Strong. Aspect: About 45° from

5

25

30

lateral branch axis. Texture and luster: Smooth, glabrous; moderately glossy. Color: Close to 144A.

Pedicels.—Length: About 3.3 cm. Diameter: About 2.5 mm. Strength: Strong. Aspect: About 30° from peduncle axis. Texture and luster: Smooth, glabrous; moderately glossy. Color: Close to 146C.

Reproductive organs.—Stamens: Quantity and arrangement: Typically five; basifixed; anthers connivent. Filament length: About 2 mm. Filament color: Close to 145D. Anther shape: Narrowly sagittate. Anther size: About 2.3 mm by 8.8 mm. Anther color: Close to 162B. Pollen amount: Moderate. Pollen color: Close to 155B. Pistils: Quantity: Typically one. Pistil length: About 2.4 cm. Style length: About 1.9 cm. Style color: Close to 145D. Stigma diameter: About 3.1 mm. Stigma shape: Club-shaped, pointed. Stigma color: Close to 143B. Ovary color: Close to 145A.

Seeds and fruits.—To date, seed and fruit production have not been observed on plants of the new *Mandevilla*.

Pathogen & pest resistance: To date, plants of the new *Mandevilla* have not been noted to be resistant to pathogens and pests common to *Mandevilla* plants.

Temperature tolerance: Plants of the new *Mandevilla* have been observed to tolerate temperatures ranging from about 5° C. to about 40° C. and to be suitable for USDA Hardiness Zones 9 to 13.

It is claimed:

1. A new and distinct *Mandevilla* plant named 'TVMD303' as illustrated and described.
